Primary Examiner — Susan Bennett Hattan(74) *Attorney, Agent, or Firm* — Ledgley Law; Cynthia J. Ledgley(57) **CLAIM**

The ornamental design for a leg support harness, as shown and described.

DESCRIPTION

FIG. 1 is a front perspective view of the leg support harness, depicted in an embodiment as worn by a person, showing my new design;

FIG. 2 is a front perspective view of the leg support harness, showing my new design;

FIG. 3 is a left side view of the leg support harness shown in FIG. 2, showing my new design;

FIG. 4 is a front view of the leg support harness shown in FIG. 2, showing my new design;

FIG. 5 is a right side view of the leg support harness shown in FIG. 2, showing my new design; and,

FIG. 6 is a rear view of the leg support harness shown in FIG. 2, showing my new design.

The broken lines in the drawing depict environmental subject matter only and form no part of the claimed design.
